Del., a corporation of Delaware

Application December 13, 1945, Serial No. 634,752

19 Claims. (Cl. 18—8)

1

This invention relates to the spinning of artificial filaments and is particularly concerned with a method and apparatus for imparting twist to a plurality of filaments near the position of original filament formation.

Heretofore, it has been attempted to twist the filaments formed by a spinneret by rotating the spinneret about its axis so that the bundle of filaments proceeding therefrom in the coagulating medium was twisted about its axis. In general, the twist occurred immediately at or near to the spinneret so that it was extremely difficult to rotate the spinneret at any substantial speed without completely disrupting the material forming the filaments as they leave the spinneret. Such attempts have also been accompanied with attempts to rotate the coagulating medium with the spinneret about the axis of the spinneret. In such systems heretofore proposed, it has been impossible to maintain the rotation of the coagulating medium sufficiently close to the speed of rotation of the spinneret to prevent the development of extreme turbulence and a strong force or forces tending to shear the stream of filamentary material right at the point of discharge from the spinneret face. It has also been suggested to prevent twisting and shearing at or near the spinneret face by directing the filaments proceeding from the rotating spinneret through the rotating coagulating medium to a guide in the medium which guide is offset from the axis of rotation and rotates at the same speed as the spinneret about the axis. Even in this system, great difficulties are encountered in respect to the prevention of excessive turbulence of the coagulating medium and the control by the guide depends upon the exertion of frictional forces which are detrimental to the filaments being twisted as they pass through the guide.

The present invention provides an improved method and apparatus for twisting filaments near the point of their formation which reduces to a minimum the development of turbulence in the coagulating medium. It also has the advantage of twisting the filament bundle at a region spaced a substantial distance from the spinneret but depends upon fluid forces within the coagulating medium for preventing the twisting zone from backing up entirely to the spinneret. Besides these primary objects of the invention, other ancillary objects, such as the provision of a readily laced form of equipment for executing the new process, and other ancillary advantages will be apparent from the drawing and the description thereof hereinafter.

2

In the drawing, which is illustrative of preferred embodiments of the invention,

Figure 1 is a side elevation, partly in cross-section, showing one system for carrying out the invention,

Figure 2 is an end view looking toward the left end of the apparatus shown in Figure 1,

Figure 3 is a transverse section on the line III—III of Figure 1,

Figure 4 is a transverse section taken on line IV—IV of Figure 1,

Figure 5 is a detail section taken on line V—V of Figure 1,

Figure 6 is an elevation partially in cross section, showing another embodiment, and

Figure 7 is a perspective view of the guide shown in Figure 6.

In general, the invention involves the rotation of the filaments and the coagulating medium through which they pass about a common axis which is offset from the path of the filaments through the greater length of the body of the bath and which is eccentric of the body of the bath. This causes the portion of the coagulating medium through which the filaments proceed as they pass between the spinneret and the discharge to rotate substantially in unison with the filaments up to the point of discharge. This motion prevents the development of turbulent forces in the medium adjacent the path of the filaments and likewise tends to keep the twisting point nearer the position of filament discharge from the body of the coagulating medium than the spinneret.

Referring to Figures 1 to 5, a suitable form of apparatus for producing twisted filaments in accordance with the present invention is shown and comprises a coagulating medium receptacle 2 which is carried by a supporting saddle 2a provided with a projecting sleeve 3 rotatable in suitable spaced bearings 4 and 5. A pulley 6 driven by a belt 7 and a motor or equivalent driving means (not shown) serves to rotate the system.

The coagulating medium receptacle 2 may conveniently comprise two members 8 and 9 each having an overall cross section of generally semicircular shape. The member 8 is provided with a longitudinal channel 10 for receiving the coagulating medium. The channel 10 may occupy the entire cross section of the semicircular member 8 except of course for the outer wall. However, it is preferred that the channel have a compact cross section, such as that of a square, rectangle, arcuate-bottomed, parallel-sided quadrilateral shown particularly in Figure 4, and preferably,

as shown, the lateral surfaces of the channel are disposed about an intermediate plane of symmetry in which the axis of rotation lies. This provides for the maximum economy of liquid, the smoothest flow thereof through the channel and a minimum of turbulence.

The channel 10 is provided with a supporting bracket 11 adapted to receive the duct 12 for feeding spinning material to the spinneret 13. Near the other end of the channel 10 a barrier wall 14 is provided. This wall 14 is spaced from the adjacent wall of member 9 to provide a discharge outlet for the filaments and coagulating medium. The member 8 may have a longitudinal recess or groove 15 adapted to receive a sealing gasket 16 and a complementary longitudinal projecting tongue portion 17 of the member 9 which may be a solid block of a suitable weight to properly balance with the coagulating medium-containing member 8 during rotation of the assembled unit. The member 9 may be hinged at 18.

The U-strap 19 secured to member 8 is provided with a slot 20 (see Figure 5) and a key 21 having a foot 22 extends through a suitable bore in member 9 and the slot 20 of the strap 19. The key terminates in a yoke 23 pivotally carrying a toggle lever 24. The cam 25 of the toggle lever works within a transverse groove 26 in the member 9. In the position shown in Figure 1, the toggle lever 24 is in locking position with the cam 25 engaging the groove 26 tightly. In this position, the foot 22 is set at an angle to the slot 20 as shown in Figure 5. By lifting the handle of lever 24, the cam 25 is freed from the groove 26 and the key may be rotated so that its foot 22 is in registry with the slot 20 to thereby allow release of the member 9 for swinging freely on its hinge 18. A gasket or packing 27 may be provided to seal the key 21.

Member 8 carries adjacent its discharge end a projecting sleeve 28 having a passage 29 for guiding the twisted filaments discharged from the device. The sleeve 28 may be rotatably supported in the bearing 30. Between the member 9 and the sleeve 28 there is provided a gasket 32 of semicylindrical shape which serves to prevent discharge of liquid. Gasket 32 may be formed as an integral part of gasket 16. The bearing 30 carries a splash guard 33 which surrounds the discharge end of the coagulating receptacle 2. This guard serves to catch coagulating medium discharged through the passage 34 extending between wall 14 and the inwardly extending portion of sleeve 28. The guard is also provided with an inwardly turned deflecting ring 35 to catch liquid thrown to the upper portion of guard 33 and tending to flow down the conical skirt of the guard. The guard 33 is provided with a discharge outlet 36 and liquid flowing therethrough may be deflected to any suitable drain or recovery system not shown by the plate 37. The guard 33 as shown in Figure 2, may be of hinged construction, the wing nut 31 serving to releasably secure the two hinged parts together.

The coagulating medium may be introduced into the device through any suitable means and conveniently it may be introduced through a sleeve 38 surrounding the axially extending portion 12a of the spinning material duct 12. The sleeve 38 may be rotated with the duct 12 and sleeve 3 and to assure the same speed of rotation, a seat 39 may be formed at the inner end of sleeve 38 for receiving the inclined portion of duct 12.

To lace up the embodiment shown in Figures 1 to 5, the operator, before starting rotation of

the device, opens the hinged guard 33 and swings the member 9 upwardly on the hinge 18. He then draws the filaments from the spinneret through a sleeve 28, such as by means of a suction device, and carries the filaments to the next handling device such as a godet or thread-advancing reel. He thereupon secures member 9 into closed position, closes the guard 33, and starts the motor for rotating the receptacle 2. This causes rotation of the coagulating medium in the channel 10 and the filaments with it. Since the axis of rotation of both filaments and bath is offset from the path of the filaments through substantially the entire length of the coagulating medium, (except possibly adjacent the filament-discharge end thereof) the twist is put into the bundle of filaments in the passage 29 of sleeve 28 which rotates with the system. The flow of the coagulating medium is substantially concurrent with the travel of the filaments and the development of cross currents in the coagulating medium is minimized because of the fact that centrifugal force is the main force exerted upon the medium. However, this force merely creates a pressure toward the outer wall of member 8 and a flow of the medium away from the spinneret which is controlled by the end wall 14. This end wall 14 in effect maintains a predetermined surface upon the body of coagulating medium when the device is rotating at sufficient speed to withdraw the liquid from the confining surface, such as of the gasket 16. Centrifugal force also tends to keep the filaments well out into the body of coagulating medium throughout the length thereof, except near the point of discharge into the passage 29. The provision of a narrow channel 10 of compact cross-section for the coagulating medium and filaments also serves to minimize the development of cross currents and turbulent effects. The system thus is so constructed as to assure that centrifugal force favors a smooth uniform concurrent flow of coagulating medium and filaments. The speed of rotation of this embodiment should be sufficient to maintain a definite surface on the body of coagulating medium throughout the cycle of rotation of the device.

Preferably, as shown, the axis of rotation is approximately horizontal but it is obvious that considerable inclination of the axis may be used, even a 90° inclination. Of course, when the axis is inclined, gravity effects will modify the shape of the surface of the coagulating medium to that of a vortex or approaching that of a vortex but this will not essentially change the characteristic of uniform flow relatively free of turbulent or cross-current effects.

Figures 6 and 7 show a modification arranged with the axis of rotation substantially vertical. In this embodiment, the rotating receptacle may comprise two halves 8a and 9a secured in a cup bracket 40 which has a projecting sleeve 3 corresponding to that of Figure 1. The sleeve 3 is rotatable in a suitable step bearing comprising elements 4 and 5 and may be driven by a pulley 6 and belt 7, as in Figure 1.

As in Figure 1, the coagulating medium may be introduced through the space between the sleeve 38 and the duct 12a which has the offset portion 12 terminating in the spinneret 13. If desired, the spinneret 13 may have its face inclined from the horizontal as shown. This allows of the use of greater speeds of rotation where the spinning material is of high specific gravity and would tend to be thrown out too rapidly under the

influence of centrifugal force to escape breakage of filaments because of sharp deflection of the spinning material as it leaves the spinneret orifices. The transverse cross section of the channel 10 may be substantially the same as that shown for the channel 10 in Figures 1 to 5 and it terminates in an end wall 14. However, in this embodiment, the end wall is spaced from the member 9a to provide an approximately axial discharge passage for the filaments and coagulating medium.

The coagulating medium flows radially outwardly over the top surface of the members 8a and 9a and over the ring 46 of flexible material, such as of rubber or synthetic rubber, into the guard 33a having a discharge 36a. The guard 33a may comprise an inside conical ring 41 to contain any liquids splashed back from the outer conical portion of the guard 33a. The guard 33a is carried by a bracket 42 which is slidably mounted in a pair of parallel guideways 43. The bracket 42 may also carry a stationary guide 44, more particularly shown in Figure 7. This guide may be formed of a suitable non-corrosive low-friction metallic wire bent around into the form of an overlapped ring pigtail which is readily laced and which prevents the filaments from flying out of the ring during normal operation.

In this embodiment, rotation may be effected at any speed, even at speeds giving rise to insufficient centrifugal force to cause the formation of a vortex, i. e., insufficient to cause separation of a surface of the coagulating medium away from the confining surface 45 of member 9a. The operation is similar to that described for Figures 1 to 5 but lacing may be accomplished simply by allowing the filament-forming material to flow to the top of the receptacle 2. Lacing, of course, is performed with the guard 32a moved upwardly out of the way along guideways 43. This upward motion of the guard is permitted by virtue of the flexible ring 46 which allows passage both downwardly and upwardly of the deflector 41 within the guard 33a. Centrifugal force tends to hold the filaments away from the axis of rotation and tends to prevent the insertion of twist until the bundle approaches the guide 44, such action being the result of the viscosity effects of the coagulating medium within the receptacle 10 as compared to that above such receptacle. When high speeds of rotation are involved, a vortex surface may be formed away from the upper portion of the confining surface 45, the distance along which such separation occurs depending upon this speed of rotation. However, this does not essentially disturb the uniform flow of coagulating medium with the filamentary material and as in the other embodiment, high speeds of rotation may be used without encountering serious cross current effects and the prevention of the backing up of the twist to the spinneret is under the control of the fluid medium rather than a mechanical element exerting frictional effects upon the filamentary material.

The invention is applicable to the production of artificial filamentary material of any character whatsoever by wet spinning methods. Examples are of the production of regenerated cellulose by extrusion of viscose through a spinneret into an acid or salt coagulating bath at temperatures from normal room temperature to about 50° C.; also, the production of regenerated cellulose filaments from cuprammonium cellulose; the spinning of cellulose acetate, other cellulose esters as well as cellulose ethers and other derivatives;

the spinning of resinous materials, such as the vinyl resins, particularly copolymers of vinyl chloride with vinyl acetate or acrylonitrile, nylons, vinylidene chloride, fluoride, or bromide; the spinning of proteinous materials such as casein; etc.

It is to be understood that changes and variations may be made without departing from the spirit and scope of the invention as defined in the 10 appended claims.

I claim:

1. The method of producing artificial filaments comprising extruding a filament-forming material through a spinneret directly into a body of 15 a liquid coagulating medium to form a plurality of filaments proceeding therefrom in generally the same direction along a common path and rotating the filaments and the coagulating medium as the filaments proceed therethrough bodily about a common axis offset from the path of the filaments through the medium and eccentric of the body of liquid.

2. The method of producing artificial filaments comprising extruding a filament-forming material through a spinneret directly into a body of a liquid coagulating medium to form a plurality of filaments proceeding therefrom in generally the same direction along a common path and rotating the filaments and the coagulating 25 medium as the filaments proceed therethrough bodily about a common axis outside the body of the medium and eccentric of the body of liquid.

3. The method of producing artificial filaments comprising extruding a filament-forming material through a spinneret into a body of a liquid coagulating medium to form a plurality of filaments, rotating the filaments and the coagulating medium as the filaments proceed therethrough about a common axis offset from the path of the filaments through the medium and eccentric of the body of liquid, removing the filaments from the body of coagulating medium, and then passing the filaments through a confined guiding passage while rotating the confining 40 surface thereof.

4. The method of producing artificial filaments comprising extruding a filament-forming material through a spinneret into a longitudinally flowing body of a liquid coagulating medium to 45 form a plurality of filaments, rotating the filaments and the coagulating medium as the filaments proceed therethrough bodily about a common axis offset from the path of the filaments through the medium and eccentric of the body of liquid, substantially the entire body of liquid along at least the greater part of its filament-containing length from the position of filament-extrusion being disposed on one side of the axis of rotation at any given instant.

5. The method of producing artificial filaments comprising extruding a filament-forming material through a spinneret into a body of liquid longitudinally flowing in a narrow channel bounded by two opposed lateral surfaces having

an intermediate plane of symmetry to form a plurality of filaments proceeding from the spinneret in generally the same direction along a common path, and rotating the channel containing the filaments and the bath about an axis eccentric of and outside the body of the medium disposed in the plane of symmetry with respect to the lateral surfaces.

6. Apparatus for spinning artificial filaments comprising a receptacle for a coagulating liquid 75 mounted rotatably on an axis, said receptacle

comprising a liquid-receiving channel the major portion of which is disposed to one side of the axis of rotation; a spinneret arranged to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle and spinneret about said axis.

7. Apparatus for spinning artificial filaments comprising a receptacle for a coagulating liquid mounted rotatably on an axis, said receptacle comprising a liquid-receiving channel the major portion of which is disposed to one side of the axis of rotation, a spinneret disposed in the channel away from the axis of rotation to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle and spinneret about said axis.

8. Apparatus for spinning artificial filaments comprising a receptacle for a coagulating liquid mounted rotatably on an axis, said receptacle comprising a liquid-receiving channel the major portion of which is disposed to one side of the axis of rotation, said channel having a peripheral wall and an end wall extending inwardly toward the axis of rotation but terminating short of the axis to provide a passage for discharge of the filaments, a spinneret disposed in the channel away from the axis of rotation to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle and spinneret about said axis.

9. Apparatus for spinning artificial filaments comprising a receptacle for a coagulating liquid mounted rotatably on an axis, said receptacle comprising a liquid-receiving channel the major portion of which is disposed to one side of the axis of rotation, said channel having a peripheral wall and an end wall extending inwardly toward the axis of rotation but terminating short of the axis to provide a passage for discharge of the filaments, a spinneret disposed in the channel away from the axis of rotation to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle, guide means, and spinneret about said axis.

10. Apparatus for spinning artificial filaments comprising a receptacle for a coagulating liquid mounted rotatably on an axis, said receptacle comprising two separable members one only of which is provided with a liquid-receiving channel the major portion of which is disposed to one side of the axis of rotation, a spinneret arranged to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle and spinneret about said axis.

end of the receptacle away from the spinneret for receiving the filaments discharged from the receptacle, and means for rotating the receptacle and spinneret about said axis.

5. 11. Apparatus for spinning artificial filaments comprising a receptacle for a coagulating liquid mounted rotatably on an axis, said receptacle comprising two separable members hinged to each other, one only of which is provided with a liquid-

10 receiving channel the major portion of which is disposed to one side of the axis of rotation, a spinneret arranged to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle and spinneret about said axis.

20 12. Apparatus for spinning artificial filaments comprising a receptacle for a coagulating liquid mounted rotatably on an axis, said receptacle comprising two separable members each having a generally semicylindrical shape, one only of

25 the members having a longitudinal channel disposed entirely to one side of the axis of rotation, said channel having a peripheral wall and an end wall extending inwardly therefrom toward the axis of rotation but terminating short of the axis to provide a passage for discharge of the filaments; a spinneret disposed in the channel away from the axis of rotation to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle and spinneret about said axis, the rotating assembly being substantially balanced dynamically.

30 13. Apparatus for spinning artificial filaments comprising a rotatable support, a receptacle carried by said support for rotation therewith, a spinneret in the receptacle, a supply duct connected to the spinneret and carried by the support for rotation therewith, said receptacle comprising two complementary members each extending longitudinally from a position adjacent the spinneret to a position away from the spinneret, a longitudinal channel provided in one of the members and the other having one surface facing the channel and enclosing one side of it, said latter member being pivotally mounted about an axis transverse of the rotational axis of the receptacle.

35 14. Apparatus for spinning artificial filaments comprising a rotatable support, a receptacle carried by said support for rotation therewith, a spinneret in the receptacle, a supply duct connected to the spinneret and carried by the support for rotation therewith, said receptacle comprising two complementary members each extending longitudinally from a position adjacent the spinneret to a position away from the spinneret, a longitudinal channel provided in one of the members and the other having one surface facing the channel and enclosing one side of it, said latter member being pivotally mounted about an axis transverse of the rotational axis of the receptacle.

40 15. Apparatus for spinning artificial filaments comprising a rotatable support, a receptacle carried by said support for rotation therewith, a

spinneret in the receptacle, a supply duct connected to the spinneret and carried by the support for rotation therewith, said receptacle comprising two complementary members each extending longitudinally from a position adjacent the spinneret to a position away from the spinneret, a longitudinal channel provided in one of the members and the other having one surface facing the channel and enclosing one side of it, said latter member being pivotally mounted about an axis transverse of the rotational axis of the receptacle, guide means adjacent the end of the receptacle away from the spinneret and axially disposed with respect thereto.

16. Apparatus for spinning artificial filaments comprising a rotatable support, a receptacle carried by said support for rotation therewith, a spinneret in the receptacle, a supply duct connected to the spinneret and carried by the support for rotation therewith, said receptacle comprising two complementary members each extending longitudinally from a position adjacent the spinneret to a position away from the spinneret, a longitudinal channel provided in one of the members and the other having one surface facing the channel and enclosing one side of it, said latter member being pivotally mounted about an axis transverse of the rotational axis of the receptacle, guide means adjacent the end of the receptacle away from the spinneret and axially disposed with respect thereto, means for rotating the guide means and receptacle together about their common axis.

17. Apparatus for spinning artificial filaments comprising a support rotatable on a horizontal axis, a receptacle carried by said support for rotation therewith, a spinneret in the receptacle, a supply duct connected to the spinneret and carried by the support for rotation therewith, said receptacle comprising two complementary members each extending longitudinally from a position adjacent the spinneret to a position away from the spinneret, a longitudinal channel provided in one of the members and the other having one surface facing the channel and enclosing one side of it, said latter member being pivotally mounted about an axis transverse of the rotational axis of the receptacle.

18. Apparatus for spinning artificial filaments

comprising a support rotatable on a horizontal axis, a receptacle carried by said support for rotation therewith, a spinneret in the receptacle, a supply duct connected to the spinneret and carried by the support for rotation therewith, said receptacle comprising two complementary members each extending longitudinally from a position adjacent the spinneret to a position away from the spinneret, a longitudinal channel provided in one of the members and the other having one surface facing the channel and enclosing one side of it, said latter member being pivotally mounted about an axis transverse of the rotational axis of the receptacle, guide means adjacent the end of the receptacle away from the spinneret and axially disposed with respect thereto.

19. Apparatus for spinning artificial filaments comprising a receptacle for a coagulating liquid mounted rotatably on a vertical axis, said receptacle comprising a liquid-receiving channel the major portion of which is disposed to one side of the axis of rotation, a spinneret arranged to deliver a plurality of streams of filament-forming material into the channel all on one side of the axis, means for supplying a coagulating liquid to the channel, guide means adjacent the end of the receptacle away from the spinneret for receiving the filaments discharged from the receptacle, and means for rotating the receptacle and spinneret about their common vertical axis.
